UNITED STATES PATENT OFFICE.

JAMES T. COWLEY, OF BOSTON, MASSACHUSETTS, ASSIGNOR TO THE LAMSON COMPANY,
OF NEWARK, NEW JERSEY, A CORPORATION OF NEW JERSEY.

PNEUMATIC AMMUNITION ELEVATING AND LOADING DEVICE.

1,148,077.

Specification of Letters Patent. Patented July 27, 1915.

Application filed August 8, 1906. Serial No. 329,803.

To all whom it may concern:

Be it known that I, JAMES T. COWLEY, of Boston, in the county of Suffolk and State of Massachusetts, have invented certain new and useful Improvements in Pneumatic Ammunition Elevating and Loading Devices, of which the following is a specification.

My invention relates to improvements in pneumatic ammunition elevating and loading device for guns, particularly adapted for use on shipboard, and the object is to provide means under the control of the operator in the turret for elevating a charge from the magazine to the turret and to direct and drive the charge into the breach of the gun for firing after the breach has been closed. By the use of this invention, this can be done readily and with perfect safety.

In the accompanying drawings, one form of construction embodying my invention is shown, as follows:

Figure 1 is a side elevation of the upper portion of the device located above the gun deck. Fig. 2 is a side elevation of the lower portion of the device looking below the gun deck and adjacent to the magazine, being a continuation of Fig. 1. Fig. 3 is a side view of Fig. 2. Fig. 4 is a plan view of Fig. 1 showing the mechanism for controlling and directing and driving the charge. Fig. 5 is a detail of the air control to be hereinafter described. Fig. 6 is a section on the line 6—6 Fig. 3. Fig. 7 is an enlarged view of the latch arm shown in Fig. 2. Fig. 8 is a section on line 8—8 Fig. 4.

Like letters of reference refer to like parts throughout the several views.

Starting from adjacent the magazine (Fig. 2) is a transmission tube A having the lower section or despatching inlet pivoted at B to the support B' located within the casing C, so adapted that either of the two holders or tubes b or b' comprising the inlet may be brought into alinement with the tube A by moving the lever B² fixed to the inlet. The air is supplied through the pipe D and reducing valve D' to the two-way cock D² into the pipe D³ which connects at one end with a reservoir where the supply of air is stored and which will always be at constant pressure prior to sending a charge, the other end of the pipe D³ continuing downward

connecting with the tube d through the union D⁴ which tube communicates with the bottom of the holder or tube b. A similar tube d' is connected with the bottom of the holder b' and adapted to swing into communication with the pipe D³ by means of the lever B² (Fig. 3). At the lower end of the tube A is a union consisting of a sleeve a threaded to the tube A and adapted to be secured by means of the handle a' down upon the upper end of either of the holders or tubes b b', thereby making an air-tight joint. On one side of the sleeve a is a flange a² adapted to exert a pressure upon the stud a³ thereby pressing two sections of the air supply pipe D³ and d tightly together at D⁴. It will be seen that when the sleeve a is loosened, it will rise upon the thread, and the tubes b and b' will be free to be thrown over into the opposite position (as shown in dotted lines Fig. 2) by means of the lever B². The despatching inlet is located below the level of the floor so that the openings at the upper end of the holders will be at a convenient height for receiving a charge.

When the despatching inlet is in the position shown in full lines Fig. 2 one section or holder b' is in position to receive a fresh supply of ammunition, while the other section or holder b is in alinement with the tube A and the charge is ready to be elevated to the gun. By this means there will be an extra charge of ammunition constantly ready to be elevated.

The section of the main tube A' above the gun deck is pivoted at its lower end so that it may be swung to connect with either of the tubes A² leading to either gun; this motion is controlled by means of the shaft E which is secured to the tube A' at its lower end and at its upper end is fastened to the lever E' which carries the rack E² at its outer end which may be moved by means of a pinion E³ operated by a crank E⁴. The shaft E and crank E⁴ are pivoted in bearings E⁵ E⁶ respectively. The top sections of the main tube A³ are hinged at A⁶ to the tubes A² so that they may be lifted to allow the closing of the breech of the gun as shown in dotted lines Fig. 1. The sections A¹, A², A³ are curved to form a bend by which the ammunition is carried around to the breech of the gun and delivered horizontally into the gun. This bend is impor-

tant, not only for properly delivering the ammunition to the gun, but also from its action as a retarding device to slow down the ammunition and aid in securing its delivery gently and without shock.

When the tube A^3 is in position to deliver into the gun, it is held firmly in this position by means of the lever F carrying the latch F' which engages the pin F^2 . In the rear of the lever is the stop F^3 so that when the lever is pulled away from the pin F^2 it will strike the stop F^3 and by continuing the motion of the lever F will lift the section A^3 and leave the gun entirely free of access. There is a counterbalance W connected with the sections A^3 by the cord W' , which cord is supported by pulleys W^2 to facilitate the movement of the sections and hold them in any desired position. Within easy reach of the gunner is a valve G ; when the section A' has been swung into line with one of the tubes A^2 this valve G will be operated to allow the charge of ammunition to be driven into the gun, but this will be impossible when the section A' is not in exact alinement with one of the two adjoining sections A^2 for the following reason: Secured to the valve stem of the valve G is a collar G' having a slot G^2 to allow the rack E^2 to move longitudinally through when said valve is in the position shown in Fig. 8; it will be impossible to turn the valve G except when the collar G' is in line with one of the two notches E^2 . The pipe g leads from the valve G to the pipe D^3 and will always have the air pressure in it equal to that in the reservoir. When the valve G has made a quarter turn it will allow the air to flow through the pipe g , through the valve G which will then have communication from the opening g^2 as shown in dotted lines Fig. 8 with the pipe g' which leads through the deck to the upper end of the cylinder H . This will depress the piston H^2 (Fig. 5) and through the piston rod H^2 will move the lever H^3 against the spring H^4 and disengage the handle of the lever b^6 from the notch H^5 . After the lever H^3 has been lifted as described, the lever b^6 may be turned in position to allow the air to pass directly through the valve D^2 , and through the connections hereinbefore described, into the holder b underneath the charge of ammunition, which is in position shown in dotted lines Fig. 2, thereby forcing it up through the tubes A , A' , A^2 , A^3 and into the breech of the gun.

The section of the valve D^2 is shown in Fig. 6 in its normal position, that is when the lever H^3 is engaged with the lever b^6 ; when in this position the air will pass through the pipe D , through the passage D^5 of the valve D' and will be charging the reservoir; but when the valve lever b^6 is disengaged from the lever H^3 and has made a

quarter turn, the supply of air in the reservoir will pass down through the lower portion of the tube D^3 and supply the power necessary to elevate the charge. After the charge is driven into position in the breech of the gun, the valve G will be returned to its normal position, thus making the air connection as shown in Fig. 8. In this position, the compressed air above the piston H^2 will have unobstructed passage to the atmosphere through the pipe g' and through the valve G as shown, and this will allow the piston to be returned to its uppermost position by means of the spring H^4 whereby the lever H^3 will be in position to engage the lever b^6 as soon as said lever has returned to its upright or normal position.

By means of the valves hereinbefore described it will be seen that the man in charge of the magazine will be unable to send any ammunition until the gunner is ready to receive it. When the gunner is ready he will turn the valve G which will release the lever b^6 as described and as soon as the man in the magazine is ready he may send up the ammunition. Moreover, the gunner cannot turn the valve G to release the lever b^6 , until the transmission tube A , A' is in proper position relatively to one of the sections A^2 , so that the ammunition cannot be sent up until the section A^2 is in proper position to receive it. The sections A^2 , with their pivoted sections A^3 , form receivers to either of which the ammunition may be delivered from the transmission tube A , A' , and from which receivers the ammunition is delivered to the gun.

While the conveying apparatus, as shown, delivers directly into the gun, so as to form also a loading device and one object of the invention is to provide such an ammunition conveying and loading apparatus, it will be understood that the ammunition conveying apparatus may not deliver the ammunition directly into the gun, but only to the turret in convenient position for loading by hand or other means and that the claims not limited to delivering the ammunition into the gun cover such use of the conveying apparatus.

Having thus described the nature of my invention and set forth a construction embodying the same, what I claim as new and desire to secure by Letters Patent of the United States is:

1. In a conveyer for ammunition, a gun, a transmission tube, a source of air supply connected with said transmission tube, means for inserting ammunition into said tube to be driven through the tube by said air supply, and means for directing and pneumatically driving said ammunition from said tube into said gun.

2. The combination with a gun, of a transmission tube, a source of air supply

connected with said tube, means for inserting ammunition into said tube to be driven through the tube by said air supply, means for moving the discharge end of said transmission tube into said gun, and means for admitting said air supply to said tube whereby said ammunition is directed and driven into said gun.

3. The combination with a gun, of a transmission tube, a source of air supply connected with said tube, means for inserting ammunition into said tube to be driven through the tube by said air supply, means for moving the discharge end of said transmission tube into said gun and for removing it from the gun, and means for admitting said air supply to said tube whereby said ammunition is directed and driven into said gun.

20 4. In a conveyer for ammunition, a gun, a transmission tube, a source of air supply connected with said transmission tube, means for inserting ammunition into said tube to be driven through the tube by said air supply, mechanism located near said gun for controlling the admission of the air supply to said tube, and means for directing and pneumatically driving said ammunition from said tube into said gun.

25 5. In a conveyer for ammunition, a gun, a transmission tube, a source of air supply connected with said tube, means for inserting ammunition into said tube to be driven through the tube by said air supply, and means for moving the discharge end of said tube into and out of communication with said gun, means for preventing the admission of said air supply to said transmission tube when said tube is out of communication 30 with said gun, and permitting the admission of said air supply to said transmission tube when said tube is in communication with said gun whereby said ammunition may be directed and discharged into the gun.

40 6. In a conveyer for ammunition, a gun, a transmission tube, a source of air supply connected with said tube, means for inserting ammunition into said tube to be driven through the tube by said air supply, means 45 for moving the discharge end of said transmission tube into said gun, means for locking said tube in position therein, and means for admitting said air supply to said tube whereby said ammunition is directed and driven into said gun.

50 7. In a conveyer for ammunition, a gun, means for pneumatically conveying by direct pressure ammunition to the gun and for driving by direct pressure the ammunition 55 into the gun, and a valve controlling the pneumatic conveying and driving operations.

60 8. In a conveyer for ammunition, the combination with a gun, of means for driving ammunition at a single flight from a

point outside the gun chamber to and into the gun by direct pneumatic pressure.

9. In a conveyer for ammunition, the combination with a gun, of means for driving ammunition at a single flight from a 70 point outside the gun chamber to and into the gun by direct fluid pressure.

10. In a conveyer for ammunition, the combination of a transmission tube adapted to extend from a point outside the gun 75 chamber to the gun and having its discharge end adapted to be placed in position to discharge ammunition into the breech of the gun, means for permitting ammunition to be placed in the receiving end of the transmission tube, and means for admitting fluid under pressure to the transmission tube behind ammunition which has been placed therein to cause the ammunition to be driven at a single flight to and into the gun by 80 direct fluid pressure.

11. In a conveyer for ammunition, the combination of a transmission tube adapted to extend from a point outside the gun chamber to the gun and having its discharge 90 end adapted to be placed in position to discharge ammunition into the breech of the gun, means for permitting ammunition to be placed in the receiving end of the transmission tube, and means for admitting gas 95 under pressure to the transmission tube behind ammunition which has been placed therein to cause the ammunition to be driven at a single flight to and into the gun by direct pneumatic pressure.

100 12. In a conveyer for ammunition, the combination of a transmission tube adapted to extend from a point outside the gun chamber to the gun and having its discharge end adapted to be placed in position to discharge ammunition into the breech of the gun, means for permitting ammunition to be placed in the receiving end of the transmission tube, means for admitting fluid under pressure to the transmission tube behind ammunition which has been placed therein to cause the ammunition to be driven at a single flight to and into the gun by 105 direct fluid pressure, and means in the gun chamber for controlling said fluid admission 110 115 means.

120 13. In a conveyer for ammunition, the combination of a transmission tube adapted to extend from a point outside the gun chamber to the gun and having its discharge end adapted to be placed in position to discharge ammunition into the breech of the gun, means for permitting ammunition to be placed in the receiving end of the transmission tube, means for admitting fluid 125 under pressure to the transmission tube behind ammunition which has been placed therein to cause the ammunition to be driven at a single flight to and into the gun by direct fluid pressure, and means in the gun 130

chamber for controlling through the medium of pneumatic pressure the operation of said fluid admission means.

14. In a pneumatic ammunition conveyer, 5 a transmission tube, a source of air supply connected therewith, means for inserting ammunition into said tube to be driven through the tube by said air supply, means for controlling the admission of said air supply to said tube, and means pneumatically controlled from the receiving station for locking and releasing said air admission controlling means to prevent or permit the admission of said air supply to said tube.

15. 15. In a pneumatic ammunition conveyer, a transmission tube, a source of air supply, and a despatching inlet comprising a plurality of holders, being closed at one end and provided with an air inlet and each of said 20 holders being adapted when in despatching position to form a closed connection between said source of air supply and said transmission tube whereby ammunition contained in said holder may be despatched through said 25 tube, the holder or holders not in despatching position being out of connection with said air supply and said transmission tube.

16. In a conveyer for ammunition, a despatching station, a receiving station, a 30 transmission tube extending between said stations, a source of pressure fluid supply for driving ammunition through the transmission tube from the despatching station to the receiving station, a valve at the receiving station, and connections by which 35 said valve controls the admission of the pressure fluid to the transmission tube for the despatch and transmission of ammunition from the despatching station to the receiving station.

17. In a conveyer for ammunition, a despatching station, a receiving station, a transmission tube extending between said stations, means for supplying gas under 45 pressure to the transmission tube for driving ammunition by direct pneumatic pressure from the despatching station to the receiving station and for discharging the ammunition from the tube at the receiving station, a valve at the receiving station, and connections by which said valve controls the admission of the pressure gas to the transmission tube at the despatching station for the despatch of ammunition.

55. 18. In a pneumatic ammunition conveyer, a despatching station, a receiving station, a transmission tube extending between said stations, a source of fluid supply for driving ammunition through the transmission 60 tube from the despatching station to the receiving station, and manually operated controlling devices at the despatching station and at the receiving station, both of which controlling devices are controlled from the 65 receiving station and must be properly posi-

tioned to permit transmission, the said devices at the receiving station being normally positioned to prevent despatch of ammunition from the despatching station.

19. In a pneumatic ammunition conveyer, 70 a despatching station, a receiving station, a transmission tube extending between said stations, a source of fluid supply for driving ammunition through the transmission tube from the despatching station to the receiving station, and controlling devices at both stations including means independent of the transit of ammunition for preventing the operation of the controlling devices at the despatching station for transmission until 75 the controlling devices at the receiving station are operated.

20. In a pneumatic ammunition conveyer, a despatching station, a receiving station, a transmission tube extending between said 80 stations, a source of fluid supply for driving ammunition through the transmission tube from the despatching station to the receiving station, a receiver at the receiving station, fluid controlling devices at the despatching station, a manually operated valve at the receiving station for controlling said fluid controlling devices by pneumatic pressure, and means controlled by parts of the conveyer at the receiving station for 85 holding the valve against movement for transmission except when said parts are in proper position for the reception of ammunition.

21. In a pneumatic ammunition conveyer, 100 a despatching station, a receiving station, a transmission tube extending between said stations, a source of fluid supply for driving ammunition through the transmission tube from the despatching station to the receiving station, a plurality of receivers at the receiving station to either of which the transmission tube may be connected for delivery, and means for preventing transmission except when a receiver is connected to 105 the transmission tube.

22. In a pneumatic ammunition conveyer, a despatching station, a receiving station, a transmission tube extending between said stations, a source of pressure fluid supply 115 for driving ammunition through the transmission tube from the despatching station to the receiving station, and means under the control of the operator at the receiving station for pneumatically controlling the despatch of ammunition to said receiving station.

23. In a pneumatic ammunition conveyer, a despatching station, a receiving station, a transmission tube extending between said 125 stations, a source of pressure fluid supply for driving ammunition through the transmission tube from the despatching station to the receiving station, and a valve at the receiving station under the control of the 130

operator at the receiving station and controlling the admission of the pressure fluid to the transmission tube for transmission to said receiving station.

5 24. In a pneumatic ammunition conveyer, a despatching station, a receiving station, a transmission tube extending between said stations, a source of fluid supply for driving ammunition through the transmission tube 70 from the despatching station to the receiving station, fluid controlling devices at the despatching station, an air pipe extending from the receiving station to the despatching station, and a valve at the receiving station controlling the operation of said fluid controlling devices at the despatching station through said pipe to prevent or permit the despatch of ammunition.

25. In a pneumatic ammunition conveyer, 20 a despatching station, a receiving station, a transmission tube extending between said stations, a source of fluid supply for driving ammunition through the transmission tube from the despatching station to the receiving station, a receiver at the receiving station, an air pipe extending from the receiving station to the despatching station, and means controlled by parts of the conveyer under the control of the operator at the receiving station for pneumatically controlling the despatching station through said pipe to prevent the transmission of ammunition except when said parts are in proper position.

35 26. In a pneumatic ammunition conveyer, a despatching station, a receiving station, a transmission tube extending between said stations, a source of fluid supply for driving ammunition through the transmission tube 100 from the despatching station to the receiving station, and means at the receiving station under the control of the operator at said receiving station operating pneumatically to prevent the despatch of ammunition to said receiving station until said means are in proper position.

27. In a pneumatic ammunition conveyer, a despatching station, a receiving station, a transmission tube extending between said stations, a source of fluid supply for driving ammunition through the transmission tube from the despatching station to the receiving station, an air pipe extending from the receiving station to the despatching station, and means at the receiving station under the control of the operator at said receiving station for controlling the pressure through said air pipe to control the despatch of ammunition to said receiving station.

60 28. In a pneumatic ammunition conveyer, a despatching station, a receiving station, a transmission tube extending between said stations, a source of fluid supply for driving ammunition through the transmission tube from the despatching station to the

receiving station, an air pipe extending from the receiving station to the despatching station and means under the control of the operator at the receiving station for transmitting fluid pressure through said air 70 pipe from the receiving station to the despatching station to control the despatch of ammunition to said receiving station.

29. In a pneumatic ammunition conveyer, a despatching station, a receiving station, 75 a transmission tube extending between said stations, a source of fluid supply for driving ammunition through the transmission tube from the despatching station to the receiving station, an air pipe extending 80 from the fluid supply to the receiving station and from the receiving station to the despatching station, and a valve under the control of the operator at the receiving station for transmitting fluid pressure through 85 said air pipe from the receiving station to the despatching station to control the despatch of ammunition.

30. On a pneumatic ammunition conveyer, a despatching station, a receiving station, a 90 transmission tube extending between said stations, a source of fluid supply for driving ammunition through the transmission tube from the despatching station to the receiving station, means for opening the conveyer system at the receiving station, and means controlled by the opening and closing of the conveyer system for preventing the despatch of ammunition to said receiving station after the conveyer system is 100 opened and until the conveyer system is again closed.

31. In a pneumatic ammunition conveyer, a transmission tube, a source of air supply, a despatching station, a plurality of ammunition holders at the despatching station movable into and out of despatching position and closed at one end, an air inlet on each holder for admitting air at the closed end of the holder behind the ammunition therein, 105 and means for connecting and disconnecting the air inlets to and from the air supply when the holders are in and out of despatching position.

32. In a pneumatic ammunition conveyer, 110 a transmission tube, a source of air supply, a despatching station, a plurality of ammunition holders at the despatching station movable into and out of despatching position, an air tube on each holder for admitting air behind the ammunition, and a coupling for connecting and disconnecting said tubes to and from the air supply when the holders are in and out of despatching position.

33. In a pneumatic ammunition conveyer, 115 a transmission tube, a source of air supply, a despatching station, a plurality of ammunition holders at the despatching station open at one end and closed at the other end 130

movable into and out of despatching position, an air inlet on each holder for admitting air at the closed end of the holder behind the ammunition therein, and a coupling for connecting the conveyer tube and the open end of a holder when the latter is in despatching position.

34. In a pneumatic ammunition conveyer, a transmission tube, a source of air supply, 10 a despatching station, a plurality of ammunition holders open at one end and closed at the other and mounted to move into position for connection of the open end with the transmission tube or out of said position for loading, and an air inlet on each of the holders for admitting air behind the ammunition when the holder is connected with the transmission tube.

35. In a pneumatic ammunition conveyer, 20 a gun, a transmission tube, a receiver at the gun breech, a source of fluid supply for driving ammunition at a single flight from a point outside the gun chamber into the gun through the transmission tube and receiver, and means for swinging the receiver away from the gun breech.

36. In a pneumatic ammunition conveyer, 25 a plurality of guns, a single transmission

tube, a receiver for each gun at its breech, and an air supply for driving ammunition through the transmission tube and one of the receivers to a gun, the transmission tube being provided with a movable section for connection of the transmission tube with either of the receivers and means for securing the movable section to one of the receivers during transit, whereby the ammunition is driven directly through the tube and into the receiver.

37. In a pneumatic ammunition conveyer, 40 a plurality of guns, a single transmission tube extending from outside the gun chamber, a source of fluid supply for driving ammunition through the transmission tube, and movable connections between the transmission tube and guns, whereby the ammunition may be driven by the air supply directly into either gun.

In testimony whereof, I have signed my name to this specification in the presence of 50 two subscribing witnesses, this fourth day of August A. D. 1906.

JAMES T. COWLEY.
